Letters Patent No. 1296 Dated May 1, 1866

Design for a Picture Frame

The schedule referred to in these Letters Patent and making part of the same.

To all whom it may concern:

Be it known that I, John H. Bellamy of Charlestown in the County of Middlesex and State of Massachusetts, have invented a new design for a Picture frame of which the following is a full, clear, and exact description, reference being had to the accompanying drawing, making part of this specification on which is represented a plan of my picture frame.

My invention consists in a picture frame surrounded by masonic emblems arranged and grouped together, as to produce an open-work design of an ornamental appearance.

See the said drawing A, in the frame or moulding above.

which at the top center is a eagle and is the square and enclosing the letter A, on one side of the square and on the other a ladder, and on the other side of the square a sword, heart, sword and two perpendicular parallel lines inside of which is a lock and circle; the whole being inclosed and supported by ornamental scroll work.

Off the bottom centre of the frame A, is a cavity or recess containing known as the twenty fourth grange, gavel, square, heart, plumb and travel; on one side of which is the anchor and hatch, and on the opposite side a cable tow and the forty seventh problem in Euclid, the whole being inclosed and supported by ornamental work. On each side of the frame A, is placed a pillar B, these being added to the top of each pillar what is known as the chapite, and to the top of each chapite a globe or ball.

Claims.

What I claim as my invention and desire to secure by Letters Patent is the design for a picture frame or retainer as shown and described.

Witnesses.
